APPARATUS FOR BENDING SINUOUS WIRE STRIPS INTO SPRINGS

John C. Lincoln, Scottsdale, Ariz., assignor to
The Universal Wire Spring Company, Cleve-
land, Ohio, a corporation of Ohio

Application September 1, 1948, Serial No. 47,217

8 Claims. (Cl. 140—71)

1

The present invention relates to an apparatus for manufacturing wire springs from corrugated steel wire strips in the form of a continuously corrugated wire having corrugations consisting of oppositely extended loops connected by substantially straight wire portions. Wire springs of this type generally embody substantially straight or slightly curved resting portions, and supporting portions integrally extended from the resting portions, and are shaped from corrugated wire strips of the type referred to above by twisting localized straight wire portions of the wire strips and forming the wire springs with sharp-edged bends or folds all for the purpose of counteracting load stresses in the wire springs by torsional stresses in their twisted straight wire portions.

The general object of the present invention is the provision of a wire spring forming apparatus having twisting means adapted to shape in successive steps sinuously corrugated wire strips to wire springs including a resting portion and supporting portions integrally extended from the resting portion, the twisting means embodying twisting devices arranged to successively twist localized straight wire portions of rigidly held sinuously corrugated wire strips to define the resting and supporting portions of thus produced wire springs by sharp-edged bends or folds.

Another object of the invention is the provision of a wire spring forming apparatus having twisting means adapted to shape in successive steps sinuously corrugated wire strips to wire springs including a resting portion and supporting portions integrally extended from the resting portion, the twisting means embodying twisting devices arranged to successively twist localized straight wire portions of rigidly held sinuously corrugated wire strips in one or the other direction to define resting and supporting portions of thus produced wire springs by sharp-edged bends or folds.

A further object of the invention is the provision of a wire spring forming apparatus having fluid-operated twisting means adapted to shape in successive steps sinuously corrugated wire strips to wire springs including a resting portion and supporting means integrally extended from the resting portion, the twisting means embodying twisting devices arranged to successively and in timed relation twist in one or the other direction localized straight wire portions of wire strips held in localized areas adjacent to the straight wire portions to be twisted, all for the purpose of producing wire springs having resting and supporting portions defined by sharp-edged bends or folds.

2

Still another object of the invention is the provision of a wire spring forming apparatus of the type referred to above in which some of the twisting devices are arranged to simultaneously twist localized straight wire portions near the end portions of rigidly held sinuously corrugated wire strips and in which other twisting devices are arranged to twist other straight wire portions located in the untwisted central portions of such wire strips to permit successively twisting of the rigidly held wire strips to wire springs with resting and supporting portions defined by sharp-edged bends or folds.

A still further object of the invention is the provision of a wire spring forming apparatus of the type referred to above, which apparatus includes holding and supporting means for a pair of sinuously corrugated wire strips and which includes twisting devices arranged to simultaneously twist two wire strips when held and supported by the wire spring forming apparatus.

Still other important objects of the invention are to provide a wire spring forming apparatus adapted to simultaneously, rapidly, accurately and inexpensively shape a pair of sinuously corrugated wire strips to wire springs having resting and supporting portions defined by sharp-edged bends or folds, the apparatus being of as simple a design and low cost as possible and practical and efficient for all purposes intended.

Additional objects and novel features of construction, combinations and relations of parts by which the objects in view have been attained, will appear and are set forth in detail in the course of the following specification.

The drawings accompanying and forming part of the specification illustrate certain practical embodiments of the invention, but it will be apparent as the specification proceeds that the structure may be modified and changed in various ways without departure from the true spirit and broad scope of the invention.

In the drawings:

Fig. 1 is a plan view of a wire spring forming apparatus constructed in accordance with this invention;

Fig. 2 is a side view of the wire spring forming apparatus shown in Fig. 1; and

Fig. 3 is an end view of the left end of the apparatus shown in Fig. 2,

Fig. 4 is a fragmentary plan view of the wire forming apparatus when forming the outside bends of a wire strip;

Fig. 5 is a fragmentary side view of a fragmentary wire spring formed with outside bends.

Fig. 6 is a fragmentary plan view of the wire

forming apparatus after having completed all bends on the wire strip; and

Fig. 7 is a fragmentary side view of the finished wire strip;

Fig. 8 is an enlarged, longitudinal sectional view through one of the wire twisting devices forming part of the wire spring forming machine, the section being taken on line 8-8 of Fig. 1;

Fig. 9 is a cross-sectional view, partly in elevation, through the wire twisting device shown in Fig. 8, the section being taken on line 9-9 of Fig. 8;

Fig. 10 is a plan view of the pressure-fluid controlling valve arrangement and the timing device for said arrangement;

Fig. 11 is a diagram disclosing the electrical and pneumatic hook-up of the different wire twisting devices of the wire forming apparatus;

Fig. 12 is a longitudinal sectional view through one of the valve members, the section being taken on line 12-12 of Fig. 10; and

Fig. 13 is a cross sectional view through the valve member, the section being taken on line 13-13 of Fig. 12.

Fig. 14 is a vertical sectional view on line 14-14 of Fig. 4.

Referring now more in detail to the drawings, the apparatus for forming sinuously corrugated wire strips into wire springs having a resting portion and supporting members integrally extended from the resting portion embodies a frame structure 2 mounted on upright 3. Frame structure 2 consists of two symmetrically arranged, elongated base plates 4 and 4' which extend lengthwise of the frame structure in parallel, spaced relation with respect to each other and are secured to each other by cross bars 5 and 5' supporting two elongated plates 6, 6' arranged edgewise on said cross bars in spaced relation to each other between the base plates 4 and 4'.

The base plates mount a plurality of pairs of twisting devices, to wit: 7-7', 8-8' and 9-9', each pair of which has one twisting device supported on base plate 4 and the other twisting device supported on base plate 4'. The steel plates 6 and 6' have attached thereto symmetrically arranged, longitudinally spaced pairs of supporting plates 10-10' and 11-11', each pair of which has one plate extended laterally from steel plate 6 and its other plate extended laterally from steel plate 6'. The pairs of supporting plates form parallelly arranged, laterally spaced, supporting members for corrugated wire strips to be twisted to wire springs. The supporting members include locating members 12, 12', to properly locate the wire strips on these supporting members and align the wire strips with the twisting devices. Lateral movement of wire strips supported and located on the supporting members is prevented by spring controlled, pivotally supported angle members 14 and 14' which are pivoted on pins 15, 15' on angle plates 16, 16' attached to base plates 4 and 4' by screws 17.

Frame structure 2, in addition to the pairs of twisting devices 7-7', 8-8' and 9-9', supports a single twisting device 18 seated on the edge-wise mounted steel plates 6 and 6' and symmetrically arranged with respect to the wire strip supporting members (plates 10, 10' and 11, 11') to permit simultaneous action on wire strips resting on the two supporting members as will be later described.

All the twisting devices, with the exception of

twisting device 18, are of substantially similar construction; therefore, detailed description of one of the twisting devices will be sufficient for all such devices.

These twisting devices each include a frame member 19 which embodies a plate member 20 (see Figs. 3 and 9) secured to the respective base plates 4 or 4' so as to extend beyond the front edge 21 of such plate and a support and guide member 22 suspended from plate member 20 and consisting of two parallelly arranged, L-shaped bars 23 and 24 secured to plate member 20 and coupled with each other by a cross bar 25. The plate member 20 mounts a vertically-arranged, double-cylinder piston unit 26 including a double piston member 29 arranged in two axially-aligned cylinder elements 27 and 28, which have different cylinder bores and are axially adjustably secured to each other. Cylinder element 27, the cylinder with the larger bore, has integrally extended therefrom a sleeve member 30, which is sleeved upon cylinder element 28 and is tightly clamped thereto by a screw member 31 extended through ear portions 32 on the slit end portion 33 of sleeve member 30. The double piston member 29 includes a piston 34 for cylinder element 27, a piston 35 for cylinder element 28 and a ratchet bar 36 connecting the pistons 34 and 35 with each other.

Double cylinder piston unit 26 effects rotation of an axially shifttable twisting shaft 37. Thus the ratchet bar 36 meshes a wide spur gear 38 mounted on twisting shaft member 37, which member is rotatably supported on a slide 39 provided with spring holding means 40 (see Figs. 1, 3, 4 and 6). This slide is guided by a slide support 41 attached to frame member 19 and shifted in one direction by a tension spring 42 secured to a stud 43 on the respective base plate 4 or 4' and a hook member 44 on a downwardly extended tripping pin 45 secured to the rear end 46 of the slide 39. This tension spring yieldingly forces the slide 39 and shaft member 37 toward the respective spring supporting member for engagement with a wire strip 47 supported thereby. Each spring holding means 40 includes a horizontally slotted member 48 dimensioned and located to be sleeved upon a loop 49 on the far side of the wire strip 47 by traversing such spring between two adjacent loops 50 on the near side of the spring, and each twisting shaft member 37 carries at its front end a crank arm 51 having slotted means adapted to engage one of the said two adjacent loops 50 on the near side of the spring when the slide 39 carrying the twisting shaft member 37 is shifted toward the spring.

Double cylinder piston unit 26 furthermore controls the action of a horizontally arranged cylinder piston member 52 (see Figs. 3 and 8) embodying a cylinder 53 attached to the support and guide member 22 between the L-shaped bars 23 and 24 thereof, and a piston 54 mounted in cylinder 53. This piston includes a piston rod 55 which extends from said piston to and through a passage 56 in the cross bar 25 of the support and guide member 22. The piston rod 55 has attached thereto by means of screw members 57 a tripping member 58 which is yieldingly forced by its spring portion 59 upwardly and engages with the downwardly extended tripping pin 45 on slide 39 when such slide has been shifted toward the respective spring supporting member. This tripping member includes a tripping plate 60 provided with an opening 61 for the tripping pin 45 to permit holding and releasing of slide 39

and positioning of shaft member 37 in twisting operations. A tension spring 62 secured to a hook 63 on cylinder 53 and a pin 64 on piston rod 55 yieldingly forces piston 54 toward the respective spring supporting member whenever the fluid pressure in cylinder 53 is released, an action which permits automatic coupling of slide 39 with piston rod 55 for resetting of the twisting device after each twisting operation as will be later described.

To control the angle of twist to be applied to a straight wire portion of wire strip 47, the length of the stroke of double piston member 29 is made adjustable. This is effected by a threaded bolt 65 (see Fig. 9) threaded into the head 66 of cylinder element 27 and held in adjusted position by a lock nut 67. Bolt 65 arrests the upward movement of double piston member 29, the downward movement of which member is arrested by engagement of lower end portion 68 of double piston member 29 with the head 69 of the cylinder element 28.

Actuation of the pairs of twisting devices 7-7', 8-8' and 9-9' is effected by fluid under pressure fed into their double-cylinder piston units 26 through two valve controlled fluid pressure lines 70, 71 and a third uncontrolled fluid pressure line 72. For such purpose each cylinder element 27 has arranged in its cylinder head 66 a passage 73 which is in open communication with one of the valve controlled pressure lines 70 and 71, that is, the cylinder elements 27 of the twisting devices 7-7' and 9-9' have their passages 73 in open communication with valve controlled pressure line 70 and the cylinder heads of twisting devices 8-8' have their passage 73 in open communication with valve controlled pressure line 71, and each cylinder element 28 has arranged in its cylinder head 69 a passage 74 which is in open communication with the fluid pressure line 72. In addition the horizontally arranged cylinder 53 of each twisting device communicates through a short pipe line 75 with the cylinder element 28 of such device. For such purpose cylinder 53 includes a bore 76 in its cylinder head, and cylinder element 28, a bore 77 in the cylindrical side wall 78 of the cylinder element 28, which two bores 76 and 77 communicate with each other through pipe line 75. Bore 77 in side wall 78 is located to effect in the lowest position of double piston member 29 free communication of cylinder 53 with the open atmosphere, such communication taking place from cylinder 53 through bore 76, pipe line 75, bore 77, cylinder element 28 and the large opening 79 (see Figs. 2 and 9) in sleeve member 30, through which opening spur gear 38 extends for engagement with ratchet bar 36.

The twisting devices of each pair of the pairs of twisting devices 7-7', 8-8' and 9-9' oppose each other. Each pair of these twisting devices includes a left-handed and a right-handed twisting device to attain identical bends in opposed straight portions of wire strips 47 placed on the laterally and longitudinally spaced supporting plates 10, 10' and 11, 11'. In addition, corresponding twisting devices of the pairs of twisting devices 7-7' and 8-8' have for twisting operations the twisting shafts 37 rotated in the same directions, whereas the twisting shafts 37 of the pair of twisting devices 9-9' in twisting operations are rotated in a direction opposite to rotation of the corresponding shafts of the pairs of the twisting devices 7-7' and 8-8'.

The single twisting device 18 (see Figs. 1, 2, 75

3, 4 and 5) which is directly seated on the edge-wise mounted steel plates 6, 6' includes only a double cylinder piston unit 80 constructed substantially similar to the double cylinder piston unit 26 previously described. Unit 80 carries in its two axially aligned cylinder elements 81 and 82 a double piston member 83, the ratchet bar 84 of which is arranged to effect rotation of a large spur gear 85 rigidly mounted on a shaft 86 which is rotatably supported in bearings 87. Shaft 86 carries at its opposite ends crank arms 88 having slotted means 89 arranged to engage a single loop on the far side of springs resting on the wire strip supporting members referred to above.

While the slotted means 48 on the spring holding means 40 of wire twisting devices 8-8' and 9-9' are sized to substantially fit the gage of the wire of the wire strips 47, the slotted means 91 on the spring holding means of wire twisting devices 7-7' are sized to fit the slotted means 89 on crank arms 88 so as to positively lock spur gear 85 against rotation when the spring holding means 40 of wire twisting devices 7-7' have been shifted with slide 39 toward the springs.

Fluid under pressure is fed into the pipe lines of the spring forming apparatus through a pipe 92 (see Figs. 2, 10 and 11) into a distributing fitting 93 having three outlets 94, 95 and 96 (see Fig. 11) connected with the valve controlled fluid pressure lines 70, 71 and the uncontrolled fluid pressure line 72, respectively. Each of the valve controlled fluid pressure lines 70 and 71 include a solenoid operated valve member 97 and 97', respectively, with a valve body 98 mounting an axially shiftable, spring controlled valve 99 (see Figs. 10 and 13). Valve body 98 includes a through bore 100 for the elongated, cylindrically shaped valve 99 which is fully extended through bore 100, and oppositely arranged inlet and outlet passages 102 and 101 extended from bore 100. The valve 99 which is provided with a circumferential recess 103 controls the inlet and outlet passages 102 and 101 so that in one position of said valve the passages 102 and 101 are shut off from each other and in another position communicate with each other through the circumferential recess 103 in said valve. In addition, valve 99 includes a channel 104 in the peripheral wall of said valve which channel is arranged parallel to the axis of the valve and effects communication of the outlet passage 101 of valve body 98 with the open atmosphere only when valve 99 shuts off communication of inlet passage 102 with outlet passage 101.

The thus constructed valve members 97 and 97' are yieldingly held into position to shut off communication between their intake and outlet passages by compression springs 105-105', respectively, in which position the outlet passage communicates through channel 104 with the open atmosphere—and for communication between such inlet and outlet passages are shifted by an electromagnet 106, the armature 107 of which is attached to the outwardly exposed end portion 108 of elongated valve 99. There are two electromagnets 106 and 106' for fluid pressure lines 70 and 71, respectively, which electromagnets are controlled by a timer arrangement 109 rotated by a motor 110. This timer arrangement includes a rotary switch drum 111 which is rotated by the motor over a worm drive 112 and provided with contact segments 113 cooperating with spaced, stationary contact members 114, 115 and 116 in timing the energizing of

the coils 111, 117' of electromagnets 106 and 106' for timed shifting of valve members 97 and 97' by said electromagnets. The switch drum 111 is mounted on a shaft 118 journaled in bearings 119, which shaft also mounts the worm gear 120 of the worm drive and includes at its end portion 121 a lever 122 actuating a trip switch 123 adapted to automatically stop rotation of motor 110 by interrupting the current after each complete revolution of the switch drum 111.

In the operation of the wire spring forming apparatus, two sinuously shaped wire strips 47 are placed in proper position on the supporting members (supporting plates 10-10' and 11-11') and then slides 39 of wire twisting devices 7-7', 8-8' and 9-9' are released by manual actuation of tripping members 58. This action effects shifting of the slides toward the wire strips 47 by the springs 42 causing engagement of the spring holding means 40 and their slotted means 48 and 91 with the wire strips and with the slotted means 89 on crank arms 88, respectively, and engagement of the slotted means of crank arms 51 with the wire strips. When thus readied for wire twisting operations, the wire spring forming apparatus is started by tripping trip switch 123 which controls the circuit for the motor 110, effecting rotation of switch drum 111. A rotation of this switch drum effects successively energizing and de-energizing of the coils 111 and 117' of electromagnets 106 and 106' and thus successive shifting of valve members 97 and 97'. When the valve member 97 is actuated by electromagnet 106, valve member 97' is in inoperative position and, when the valve member 97' is actuated by electromagnet 106', valve member 97 is in inoperative position.

The actuation of valve member 97 permits fluid under pressure to enter the fluid pressure line 70 so as to pass through passages 73 in cylinder heads 66 into the cylinder elements 27 of the pairs of twisting devices 7-7' and 9-9'. This pressure fluid shifts the double piston members 29 of these devices downwardly to effect rotation of their twisting shafts 37 and therewith twisting of the wire strips by ratchet bars 36 meshing the spur gears 38 to produce the bends illustrated in Fig. 5. Downward shifting of double piston members 29 is opposed by fluid under pressure passing from uncontrolled fluid pressure line 72 into cylinder elements 28 and tending to shift the double piston members 29 in an upward direction; however, this counterforce is overcome by the differential bores of cylinder elements 27-28 and 81-82, cylinder members 27 and 81 having bores substantially larger than the bores of cylinder elements 28 and 82. At the end of the downward stroke of the double piston members 29 their pistons 35 have passed the bores 77 in the side walls 78 of the cylinder elements 28 so that cylinders 53 can communicate through pipe lines 75 with the open atmosphere and that tension springs 62 can shift the piston 54 and therewith the tripping members 58 on piston rods 55 backwards (towards the left in Fig. 8) into tripping engagement with pins 45 on slides 39. De-energizing of the electromagnet 106 permits automatic resetting of valve member 97 by spring 105 to effect communication of cylinder 27 with the open atmosphere through the channel 104 of the valve member and upward shifting of the double piston members 29 back to their initial position by fluid under pressure in fluid pressure line 72 communicating with the cylinder elements 28. In this upward movement of the double piston members 29 when their pistons 35 have passed the bores 77 in

the side walls of the cylinder elements 28, communication is effected between the latter cylinder elements and cylinders 53 of cylinder-piston members 52 so that fluid under pressure from fluid pressure line 72 is fed through pipe lines 75 into cylinders 53. This fluid, which enters cylinders 53 when the twisting tension on a spring to be twisted is substantially released, shifts the pistons 54 and the slides 39 coupled with piston rods 55 of said pistons by the tripping member 58, outwardly into starting positions to disengage the spring holding means and crank arms of the pairs of wire twisting devices 7-7' and 9-9'.

The actuation of valve member 97' permits fluid under pressure to enter fluid pressure line 71 so as to pass through passages 73 into the cylinder elements 27 of the pair of twisting devices 8-8' and the single twisting device 18. This pressure fluid shifts the double piston members 29 and 83 of these devices downwardly to effect rotation of their twisting shafts 37 and 86 and therewith twisting of the wire strips by ratchet bars 36 meshing the spur gears 38 and ratchet bar 84 meshing the large spur gear 85 thereby producing the finished spring illustrated in Fig. 7. Downward shifting of the double piston members 29 and 83 is opposed by fluid under pressure passing from uncontrolled fluid pressure line 72 into cylinder elements 28 and 81 and tending to shift the double piston members 29 and 83 in an upward direction; however, this counterforce is overcome by the differential bores of cylinder elements 27-28 and 81-82, cylinder members 27 and 81 having bores substantially larger than the bores of cylinder elements 28 and 82. At the end of the downward stroke of the double piston members 29, their pistons 35 have passed the bores 77 in the side walls of the cylinder elements 28 so that cylinders 53 can communicate through pipe lines 75 with the open atmosphere and that tension springs 62 can shift the pistons 54 and therewith the tripping members 58 on piston rods 55 backward into tripping engagement with slides 39. De-energizing of the electromagnet 106' permits automatic resetting of valve member 97' by spring 105' to effect communication of cylinders 27 and 81 with the open atmosphere and upward shifting of the double piston members 29 and 83 back to their initial position by fluid under pressure in fluid pressure line 72 communicating with the cylinder elements 28 and 82. In this upward movement of the double piston members 29, when their pistons 35 have passed the bores 77 in the side walls of the cylinder elements 28, communication is effected between the latter cylinder elements and cylinders 53 of cylinder piston members 52 so that fluid under pressure from fluid pressure line 72 is fed through pipe lines 75 into cylinders 53. This fluid, which enters cylinders 53 when the twisting tension on a spring to be twisted is substantially released, shifts the pistons 54 and the slides 39, which are coupled with the piston rods 55 by tripping member 58, outwardly into starting positions to disengage the spring holding means and crank arms of the pair of wire twisting devices 8-8'.

Shortly before the end of each complete revolution of switch drum 111, lever 122 at the end portion 121 of shaft 118 actuates trip switch 123 which controls the motor circuit and when thus actuated automatically opens such circuit after each cycle, a cycle being defined by a complete revolution of switch drum 111. When the wire strips are formed to wire springs with localized twists in straight wire portions of the springs,

such springs are removed and other wire strips are placed in the apparatus for twisting these strips in the manner described above.

Having thus described my invention, what I claim is:

1. In a machine for forming wire springs from sinuously corrugated wire strips, a plurality of wire twisting devices, each including a frame, a slide on said frame, spring means for shifting said slide in one direction, shifting means for shifting said slide in the opposite direction including releasable coupling means with said slide, and shifting means for rotating said wire twisting shaft in opposite directions, said shifting means for said slide being associated with said shifting means for said wire twisting shaft to effect timed shifting of said slide in predetermined positions of the shifting means for said wire twisting shaft.

2. In a machine for forming wire springs from sinuously corrugated wire strips, a plurality of wire twisting devices, each including a frame, a slide mounted on said frame, a spring member for shifting said slide in one direction, a fluid operated cylinder-piston member including a piston releasably coupled with said slide and adapted to shift same in the opposite direction, a second spring member yieldingly counteracting shifting of the piston of said cylinder-piston member by fluid under pressure, a second fluid-operated cylinder-piston member including a piston coupled with said wire twisting shaft for rotating same in opposite directions, and a controlled fluid passage connecting the cylinders of said two cylinder-piston members, said passage being controlled by the piston of said second cylinder-piston member to effect fluid pressure of said first cylinder-piston member only at predetermined positions of the piston of said second cylinder-piston member.

3. A machine for forming wire springs from sinuously corrugated wire strips, as described in claim 2, wherein the piston of the first cylinder-piston member and the said slide include co-operating coupling members for automatically and releasably coupling said piston and slide when same are in predetermined position.

4. In a machine for forming wire springs from sinuously corrugated wire strips, a plurality of fluid operated wire twisting devices, each including an axially shiftable and rotatable wire twisting shaft, a cylinder-piston member coupled with said shaft for rotating same, a second cylinder-piston member releasably coupled with said shaft for axially shifting same, and a valve controlled fluid passage connecting the cylinders of said two cylinder-piston members, said fluid passage being controlled by the piston of said first cylinder-piston member to effect shifting of the piston of said second cylinder-piston member in a predetermined position of the piston of said first cylinder piston member.

5. In a machine for forming wire springs from sinuously corrugated wire strips, parallelly arranged supporting members adapted to support two sinuously corrugated wire strips in parallelly aligned relation with respect to each other, a plurality of spaced wire twisting devices arranged at right angles to said supporting members adjacent to the outer sides thereof, each of said wire twisting devices adapted to effect a single torsional twist in a wire strip mounted on the supporting means adjacent to such twisting device, and a wire twisting device arranged be-

tween said two supporting means, having an axially rotatable twisting shaft adapted to engage simultaneously two corrugated wire strips when supported on said supporting means and effect by a single operation localized torsional twisting in both said wire strips.

6. In a machine for forming wire springs from sinuously corrugated wire strips, parallelly arranged supporting members adapted to support two sinuously corrugated wire strips in parallel relation with respect to each other, a plurality of pairs of spaced wire twisting devices arranged at right angles to said supporting members adjacent to the outer sides thereof, and a single wire twisting device arranged between said supporting means having a rotatable twisting shaft extended at right angles to said supporting members, said twisting shaft including wire strip engaging means at its opposite ends for effecting simultaneous torsional twisting of localized areas of two wire strips supported on said wire strip supporting members.

7. In a machine for forming wire springs having angularly related contiguous areas from straight sinuously corrugated wire strips, a base, members on said base for supporting one of said strips along the length of said strip, said supporting members being spaced intermediate the ends of said strip, means attached to one of said members for locating said strips on said supporting members, a plurality of laterally spaced wire twisting devices mounted on said base adjacent the space between said supporting members and extending toward said strip, said wire twisting devices each including a shiftable frame arranged to be shifted in a plane parallel to said supporting members and toward said strip for engaging said twisting devices with portions of said strip, slotted wire holding members mounted on said frame for engaging said strip adjacent to the portions engaged by said twisting devices, and means for successively shifting said frame and actuating said twisting devices.

8. In a machine for forming wire springs having angularly related contiguous areas from sinuously corrugated wire strips, a base, members on said base for supporting one of said strips along the length of said strip, said supporting members being spaced intermediate the ends of said strip, means on one of said members for locating said strips on said supporting members, a plurality of laterally spaced wire twisting devices mounted on said base adjacent the space between said supporting members and extending toward said strip, said wire twisting devices each including a shiftable, slotted wire holding member and a shiftable, rotatable wire twisting member said wire holding members arranged to be shifted toward said strip in a plane parallel to said supporting members for engaging with portions of said strip, and said wire twisting members arranged to be shifted toward said strip in said shifting plane of the wire holding members for engaging said strip adjacent to the portions engaged by said wire holding members and an individual actuating means for each one of said wire twisting devices, each actuating means effecting in the wire twisting device controlled thereby shifting of the wire holding member and the wire twisting member and thereafter rotation of the wire twisting member.

JOHN C. LINCOLN.
